UNITED STATES PATENT OFFICE.

ROSS M. STUMM, OF PHILADELPHIA, PENNSYLVANIA, ASSIGNOR TO WESTINGHOUSE ELECTRIC & MANUFACTURING COMPANY, A CORPORATION OF PENNSYLVANIA.

TRANSMISSION-LINE DEVICE.

Application filed October 20, 1927. Serial No. 227,451.

My invention relates to transmission-line devices and particularly to electrostatic-field-control structures for high-voltage suspension insulators.

- 5 One object of my invention is to provide a device of the above-indicated character that shall be protected against damage by movement of the line conductor under certain conditions.
- 10 Another object of my invention is to provide a substantially annular electrostatic-field-control structure that may be mounted and demounted relative to its position about an insulator, while the latter is in operative 15 position between the line conductor and a main support.

A further object of my invention is to provide a transmission-line device that shall be simple and durable in construction, economical to manufacture and effective in its operation.

In transmission-line practice, it has been usual to provide electrostatic-field-control structures, such as arcing rings and shields, 25 about the insulator axis adjacent to the ends of the insulator.

By reason of the lateral extent of these members, when the conductor breaks or when violent line oscillations occur, the conductor 30 sometimes engages the perimeter of the ring or shield with sufficient force to permanently distort the latter and render it unfit for further effective service.

Also, where annular field-control-rings or 35 shields are constructed of one integral piece or are assembled as one integral structure for mounting, as such, relative the insulator, the latter has been required to be detached either from its main support or tower, or 40 from the conductor, in order that the field-control device may be placed therearound.

It is my aim to overcome the above-mentioned objections and to provide a transmission-line field-control device that has other 45 advantages.

Accordingly, in practicing my invention, I provide an electrostatic-field-control element of substantially annular shape, in general, that is provided with spaces above the conductor whereby the latter may pass into the spaces, under certain conditions, without injuring the device which is further constructed to compensate the field for the spaces thus

provided and to permit its installation about the insulator axis while the insulator is in 55 operative position.

Figure 1 of the accompanying drawing is a side elevational view of a structure embodying my invention,

Fig. 2 is a plan view of the structure shown 60 in Fig. 1, parts being broken away and omitted, and

Fig. 3 is a view, similar to Fig. 2 and on a reduced scale, of a modified form of my invention. 65

Referring to Figs. 1 and 2, the device comprises, in general, a suspension clamp 2 for supporting a conductor 3, an insulator 4 and a field-control device 5 of my invention.

The clamp 2 may be of any usual or well-known type, but, as herein illustrated, is of a type recently suggested, whereby the conductor 3 is normally securely held but is permitted to slip therethrough under certain abnormal conditions, such as breakage of the conductor between insulators. This clamp is fully set forth in a co-pending application of N. A. Wahlberg, Serial No. 209,441, filed July 30, 1927, and assigned to the Westinghouse Electric and Manufacturing Company, 70 and comprises a lower channel member 7 constituting one clamping portion, an upper clamping shoe 8, a leaf spring 9 for resiliently biasing the shoe 8 against the conductor 3 in the channel member 7, by means of a cam 75 and a lug structure (not shown), between the arms of a yoke member 10. The latter is pivotally attached to the channel member 7 by means of trunnions 12 that are secured in position opposite the conductor 3 by links 14 80 and a bolt 15.

The detailed construction and operation of the clamp 2 are not particularly germane to this invention, as claimed, it being sufficient to note, for the purpose herein disclosed, that 95 the above-mentioned slipping action takes place when the yoke 10 and the channel member 7 are angularly moved a certain amount about the axis of the trunnions 12.

As viewed in Fig. 1, it can be seen that, 100 were the device 5 completely annular in shape, any considerable angular change between the conductor 3 and the vertical axis of the insulator 4 would be likely to cause the conductor 3 to engage the structure 5.

105 In accordance with this invention, how-

ever, the device 5 comprises a field-control element 17 that is of substantially annular shape, in general, but has spaces 18 opposite the conductor 3, into which the latter may move under the above-mentioned conditions.

To compensate the field for the portions of the device which are omitted to provide the spaces 18, the oppositely disposed half portions of the element 17 may be provided with spherical or otherwise constituted end portions 20.

Supporting elements 22 of substantially U-shape may be secured, at their closed inner ends, to bosses 23 on the yoke 10, as by bolts 24, and, at the outer ends thereof, to lugs 25 on the element 17, as by bolts 26.

Under normal operating conditions, the element 17 functions substantially as an ordinary arcing ring, but when, for any cause, the conductor 3 moves toward the element 17 a sufficient distance, the conductor passes through the spaces 18 and returns therethrough to normal position, when normal conditions are restored, without having damaged the field-control device 5.

Further, since the field-control device 5 is constructed in separately mountable and demountable half portions, it may readily be mounted in operative position, without detaching the insulator 4 from either end.

In the modification of my invention illustrated in Fig. 3, in which corresponding parts are designated by corresponding reference characters, the structure is substantially the same as that described above, except that, instead of the tubular or rodlike half elements 17, that are connected by the supporting elements 22, a one-piece shield 28 of relatively thin sheet metal is substituted therefor.

The half portions of the shield 28 may be joined as in the above-described structure, but, as shown, they are integrally united by a web portion 29 at one side of the yoke 10.

A similar web or supporting element 30 may be removably connected between the halves at the opposite side of the yoke 10, as by bolts 31, to permit the shield to be placed around the axis of the insulator while the latter is in operative position, or the element 30 may constitute an integral part of the shield, as desired.

The shield 28 may be secured to the bosses 23 on the yoke 10 by L-members 32 each having a vertical arm 33 secured to the bosses, as by the screws 24 shown in Figs. 1 and 2, and a horizontal arm 34 on which the shield rests and is secured thereto, as by screws 35.

By my invention, an extremely simple and economical structure is provided that permits of ready mounting and is effective in operation, has the other advantages above-mentioned, and is, in general, an improvement in the service for which it is intended.

While I have shown and described particu-

lar forms of my invention, changes may be effected therein without departing from the spirit and scope thereof as set forth in the appended claims.

I claim as my invention:

1. In a transmission-line device, the combination with an insulator, of an electrostatic-field-control structure comprising spaced portions at opposite sides of the line conductor between which the conductor may freely pass.

2. In a transmission-line device, the combination with an insulator, of an electrostatic-field-control structure extending laterally relative to the insulator axis and having spaced perimetral portions between which the line conductor may freely pass.

3. In a transmission-line device, the combination with an insulator, of an electrostatic-field control structure of substantially annular shape, in general, extending laterally to the insulator axis but having an opening in the perimeter thereof through which the line conductor may pass.

4. In a transmission-line device, the combination with an insulator, of an electrostatic-field-control structure comprising separately mountable and demountable spaced portions at opposite sides of the line conductor between which the conductor may pass.

5. In a transmission-line device, the combination with an insulator, of an electrostatic-field-control structure comprising spaced portions at opposite sides of the line conductor between which the conductor may pass only under predetermined line conditions.

6. In a transmission-line device, the combination with an insulator and a clamp for normally holding the line conductor and permitting the same to slip relative thereto, of an electrostatic-field-control structure comprising spaced portions at opposite sides of the conductor between which the conductor may pass under conditions which cause the conductor to slip.

7. In a transmission-line device, the combination with an insulator, of an electrostatic-field-control structure comprising spaced portions at opposite sides of the line conductor between which the conductor may pass and means for compensating the field for the space between said portions.

8. In a transmission-line device, the combination with an insulator, of an electrostatic-field-control structure of substantially annular shape, in general, extending laterally to the insulator axis but having a space in the perimeter thereof in which the line conductor may be received, said structure being shaped adjacent to said space to compensate the field therefor.

9. In a transmission-line device, the combination with an insulator, of an electrostatic-field-control structure of substantially annular shape, in general, disposed about the

insulator axis but having a space in the perimeter thereof in which the line conductor may be received and being constructed for mounting and demounting relative to the insulator while the latter is in operative position between the conductor and a main support.

10. A transmission-line device comprising a substantially annular electrostatic-field-control element having diametrically opposite perimetral spaces permitting the line conductor to move freely across the perimeter when the element and the conductor move angularly relative to each other a certain 15 distance.

11. A transmission-line device comprising a substantially annular electrostatic-field-control element constructed of half portions providing diametrically-opposite spaces between the halves extending inwardly from the 20 perimeter of the annular element.

12. A transmission-line device comprising a substantially annular electrostatic-field-control element including half annular portions having spaced adjacent ends and an 25 intermediate mounting portion.

In testimony whereof, I have hereunto subscribed my name this 30th day of Sept., 1927.

ROSS M. STUMM.
